UNITED STATES PATENT OFFICE.

GEORGE W. MORRIS, OF BRANTFORD, ONTARIO, CANADA.

THRASHING-MACHINE.

SPECIFICATION forming part of Letters Patent No. 373,678, dated November 22, 1887.

Application filed April 15, 1885. Serial No. 162,310. (No model.)

To all whom it may concern:

Be it known that I, GEORGE WILLIAM MORRIS, of the city of Brantford, in the county of Brant, in the Province of Ontario, Canada, manufacturer, have invented a certain new and useful Improvement in Thrashing-Machines, of which the following is a specification.

This invention relates to thrashing-machines; and the novelty consists in the peculiar combination and the construction and arrangement of parts hereinafter more fully described, and then pointed out in the claim.

Figure 1 is a perspective view with part of casing removed so as to exhibit the straw-shaker and grain-deck. Fig. 2 is a perspective view with part of casing broken away so as to exhibit the location and interior of the smutter. Fig. 3 is a side elevation, partly in section, with smutter and other matter removed.

It will be noticed that the straw-shaker is divided into three sections, A, B, and C. The lower end of sections A and C are carried on a pair of hangers, D, only one of which is seen in the drawings; but it will be understood that a corresponding one is placed on the opposite side of the machine. The lower ends of these hangers are connected by a bar, (not shown,) which bar passes under and is secured to the sections A and C in any convenient way. A similar pair of hangers, E, carry the center section, B, the rod connecting the pair of hangers E passing below and clear of the outer sections, A and C, and their upper ends connected 35 to the cross-bar e, suitably secured at the front end of the machine.

F is a shaft having three cranks, the two outer cranks extending in the same direction and being connected to the sections A and C, 40 while the center crank, extending in a direction opposite to that of the outer cranks, is connected to the center section, B, ordinary bearing-boxes being provided for that purpose.

All three sections A, B, and C of the straw-shaker are formed substantially in the same way, each having two side rails, the tops of which are connected together by a series of diamond-shaped slats, the lower ends of the straw-shaker A, B, and C being covered by 45 perforated sheet-iron, so as to resist the extra wear on that portion of the straw-shaker immediately below the beater.

G is the grain-deck suspended by four spring-hangers, H, two of which are seen in the drawings, the other two being on the opposite side of the machine. Each pair of hangers is connected by a rod passing under the grain-deck. Only a portion of one of these rods is shown at h, Fig. 1.

I is the sieve-extension of the grain-deck G. 55 Its end is supported by a pair of spring-hangers, J, only one of which is seen, the other being on the opposite side of the machine. These hangers J are connected by a rod, j, which passes under and supports the free end of the extension I, and are set slightly more perpendicular than the hangers H, so that the sieve-extension I, which is hinged at a to the grain-deck G, has a motion imparted to it slightly different from the grain-deck G, which is connected to the center-shaker, B, by the pitman or rod K. When the crank-shaft F is caused to revolve, the sections A and C of the straw-shaker move together, while the center section, B, moves in an opposite direction from A and 65 C; and as it is connected to the grain-deck G by the pitman or rod K, the grain-deck moves with the center section, B, while the sections A and C of the straw-shaker move together in the opposite direction; consequently the grain-deck G and center section, B, counterbalance 70 the two sections A and C. If the grain-deck and center section should be heavier than the two outer sections, A C, of the straw-shaker, or vice versa, the crank driving the lighter 75 pair is made so as to have slightly more throw than the heavier pair, so as to compensate for the difference in the weight. By thus utilizing the grain deck to balance the straw-shaker I am enabled to get a straw-shaker with great 80 vibratory movement without injuriously shaking the machine when in operation.

As shown in the drawings, the bottom of the grain-deck G is made of corrugated iron, which has the peculiar advantage of forming a series 85 of receptacles to receive and hold the grain, so that the grain will be carried up the grain-deck toward the sieve-extension I by the reciprocating action of the grain-deck G, whereas if the deck G were a plain surface, the grain 90 would naturally fall toward the lower end. After the grain falls through the sieve-extension I it passes in the ordinary way through the fanning-mill screen, and finally finds its 95 100 105

way into the spout L, from which spout in ordinary thrashing-machines it is discharged; but in my construction I place an elevator-box, M, so that the grain will discharge from the 5 spout L into the box M. The buckets N of the elevator will then convey the grain from the elevator-box M into the smutter-barrel O. From this barrel it passes through the ordinary sieves and screens and is finally dis- 10 charged into the conveyer P, which may be made to revolve in either direction, so as to carry the grain to either side of the machine, a spout, Q, being placed at each side.

As I do not claim anything peculiar in the 15 construction of the smutter, and as any smutter would answer the purpose, it is not necessary for me to describe in detail its specific construction. The points to be observed are, first, that the smutter should be placed on the 20 top of the machine, so that the grain passing through it can readily be handled, so as to be

discharged from either side of the machine; secondly, that the bottom of the smutter shall communicate directly with the interior of the thrasher, so that any tailings or grain that 25 may fall with the tailings shall be discharged back onto the straw-shaker and be again carried through the machine.

What I claim as my invention is—

The combination, with the straw-shaker and 3c the smutter arranged above and communicating directly therewith, of the spout L, the elevator-box M at the discharge end of said spout, connecting said spout directly with the smutter, and the elevator in said box, all substantially as described, and for the purpose specified.

Toronto, March 21, 1885.

GEORGE W. MORRIS.

In presence of—

CHARLES C. BALDWIN,
W. I. GRAHAM.
